PACKING APPARATUS.

Application filed April 27, 1925. Serial No. 26,114.

This invention relates to packing apparatus for pumps of the centrifugal type. In recent practice, high-speed rotary pumps have been used for pumping gasoline or oil through long pipe lines and in their operation raise the pressure in the liquid being pumped, by stages. These pumps are run at a relatively high speed, for example, 2400 turns per minute. With this high speed of rotation, it is difficult to maintain the packing of the bearings intact; if the liquid being pumped is excluded from the packing, the shaft will run hot and the packing will burn out. For this reason, it has been the practice to permit a quantity of the liquid being pumped to escape through the stuffing boxes, but where high pressures are employed, the loss of this liquid is very considerable and becomes a decidedly uneconomical factor in the operation of such a pump. Where gasoline is being pumped in this way, the relatively large amount of gasoline which escapes along the shaft past the stuffing boxes develops a problem of how to dispose of this gasoline. With most types of packing, such gasoline in passing through the stuffing boxes becomes so discolored that it cannot be used again without being run again through the refinery. The general object of this invention is to provide a packing apparatus for overcoming these objections, and which will operate to prevent the loss of the gasoline which passes through the stuffing boxes, and to provide an organization of parts of the apparatus which will enable the pump to run continuously for a relatively long period of time without necessitating repacking. The invention is concerned with the operation of a pump which develops a high pressure in the liquid by stages and one of the objects of the invention is to provide efficient means for withdrawing the liquid which leaks into the stuffing boxes and returning the same to the suction line of the pump.

Further objects of the invention will appear hereinafter.

The invention consists in the novel parts and combination of parts to be described hereinafter, all of which contributes to produce an efficient packing apparatus.

A preferred embodiment of the invention is described in the following specification, while the broad scope of the invention is pointed out in the appended claims.

In the drawings:

Fig. 1 is a plan of a high-speed rotary pump embodying our invention.

Fig. 2 is a side elevation of the pump shown in Fig. 1.

Fig. 3 is a longitudinal vertical section taken through a pump of four-stage unit type; and

Fig. 4 is a longitudinal section taken through an ejector and its connections which is employed for effecting a return of the liquid which reaches the stuffing boxes, to the suction line pump.

In practicing our invention, we provide a stuffing box with means such as a pump or ejector for returning the liquid which leaks into the stuffing box back into the suction side of the pump. The pump or ejector is preferably actuated by the liquid under pressure which is developed by the pump, that is to say, liquid taken from the discharge side of the pump. We will now describe an embodiment of the invention as applied to an eight-stage pump composed of two single four-stage pumps, referring especially to Figures 1 and 2. In these views, 1 represents a prime mover which is coupled to the pump shaft 2, said shaft extending through two single pumps 3 with a shaft coupling 4 between the shaft sections.

In applying our invention to such a pump, we provide a connection from the pump for admitting a quantity of the liquid under pressure from the pump back into the suction side of the pump, and we also provide a connection from the stuffing box or stuffing boxes leading into the first named connection and operating to withdraw the liquid or gasoline which leaks into the stuffing box, from the interior of the pump, and in this way the gasoline from the stuffing boxes is brought back to the suction side of the pump. In accomplishing this by utilizing the high pressures which are obtainable only in a multiple stage pump and in order to regulate the pressure used at the ejector, we provide means for combining the different pressures of the different stages; in this way we regu-

late the pressure employed for entraining the gasoline from the stuffing boxes and we prefer to employ an ejector to facilitate this operation. In the present instance, we provide a suction line 5 leading into the low pressure volute 6^a.

In the operation of the pump, the gasoline passes into the second stage volute 6^b and from this volute it passes through a return 10 bend 7 into the third stage volute 6^c which in turn is connected with the fourth stage volute 6^d. From this point the gasoline leaves the right-hand pump 3 and passes by a pipe 8 over to the fifth stage volute 6^e. From 15 this point the gasoline passes in the same manner as in the other pump through the volutes 6^f, 6^g and 6^h and is finally expelled through a delivery pipe 9 at the high-pressure side of the pump.

20 We provide a plurality of connections 10 leading off from the different volutes, each provided with its own valve 11, and these connections all connect up to a pipe main 12 provided with a valve 13 between the two 25 single pumps 3. Adjacent the left hand pump 3, the pipe main 12 is provided with a connection 14 including a valve 15 and a pipe fitting in the form of an ejector 16 which is connected to the suction side of the 30 pump; in the present instance this ejector is connected so as to deliver the gasoline into the suction pipe 5. Adjacent the right hand pump, a similar connection 17 is provided, including its valve 18 and an ejector 19 which is connected to the suction pipe 35 5 at the point 20. The connections 14 and 17 are each provided with a pressure gauge 21.

The connections 16 and 17 are also each 40 provided with a valve 22.

The stuffing boxes 23 of the pump may be of any construction; in the present instance each stuffing box includes metallic packing rings 24 with a spacer ring or cage 45 25 separating the packing rings. From each stuffing box, we lead off a pipe connection 26, and these pipe connections are preferably tapped into the stuffing boxes at the cage rings 25. At the right hand pump 3, the 50 two connections 26 are connected through a T 27 and pipe 28 to the ejector 19, and each connection 26 is provided with its own valve 29.

At the left hand pump 3 a similar piping 55 arrangement is used, that is to say, we provide a pipe 30 and valve 30^a corresponding to each stuffing box, the said pipes 30 being connected through a T 31 and a pipe 32 to the ejector 16 (see Fig. 4). The two ejectors 16 and 19 are similar in construction.

As illustrated in Fig. 4, the high-pressure gasoline coming from the different pump stages may be admitted through the ejector by means of a discharge opening preferably 65 in the form of an inner nozzle 33. As the

high pressure gasoline flows through the ejectors, it produces a partial vacuum in the connections 28 and 32, which withdraws the gasoline from the stuffing boxes; in other words, the high pressure gasoline flowing through the ejector entrains the gasoline from the stuffing boxes and which is admitted around the discharge opening, preferably by a connection through the side of the ejector.

75 It will be noted that the pressure is higher than the pressure obtainable by operating any single pump or unit not operating to raise the pressure by stages; in other words, the pressure used at the ejector is higher than the rise in pressure between the stages.

The pipe connections 28 and 32 are provided with individual gauges 34 for indicating the pressure or vacuum. The rotors 35 of the pumps are keyed to the shaft, and beyond the stuffing boxes suitable bearings 36 for the shaft are provided.

85 In the operation of the pump, the compression by stages is effected by a rise in pressure of about eighty pounds for each 90 stage. By opening or closing the different valves 11 which correspond to the different stages, the pressure in the pipe connections 14 and 17 may be regulated as desired. In practice, in this pump operating with eighty 95 pounds pressure per square inch between the stages, we have found that a very satisfactory condition of the stuffing boxes results by regulating the valves of the pipe connections so as to give about one hundred twenty 100 pounds gauge pressure for the gasoline which is admitted into the ejector. With this pressure, we can maintain about a five-inch 105 vacuum on the stuffing boxes. This will withdraw the gasoline in sufficient quantities 110 to prevent waste, but will still permit enough gasoline to remain on the shaft to prevent 115 burning out of the packing.

119 Although we have described the formation of a partial vacuum to draw the liquid from the stuffing boxes, the apparatus will operate even if there is pressure existing in the stuffing boxes higher than atmospheric pressure. In any case the higher pressure liquid flowing through the ejector will withdraw 125 liquid from the stuffing boxes. Any desired pressure may be maintained in the main, by properly regulating the valves from the different stages.

130 In using the term "rotary pump" throughout the specification and claims, we do not restrict the meaning to what is commonly called a rotary pump, that is to say, by the term "rotary pump" we mean any pump in which the impeller performs its function by rotating.

135 It is to be understood that the embodiment of the invention described herein is only one of the many embodiments this invention may take, and we do not wish to be limited 140

in the practice of the invention, nor in the claims, to the particular embodiment set forth.

What we claim is:—

5. 1. In packing apparatus for a rotary pump, the combination of a shaft with stuffing boxes, a plurality of pump units on the shaft co-operating to develop high pressure in a liquid by stages, means for admitting 10 quantities of liquid under pressure higher than the rise of pressure between the different stages, back to the suction side of the pump, and connections from the stuffing boxes co-operating with said means to withdraw 15 liquid leaking into the stuffing boxes from the interior of the pump and return the same to the suction side of the pump.

2. In packing apparatus for a rotary pump, the combination of a shaft with stuffing boxes, a plurality of pump units on the shaft cooperating to develop high pressure in a liquid by stages, a connection from the pump for admitting quantities of the liquid under a pressure higher than the rise 25 of pressure between the different stages, back to the suction side of the pump, and connections from the stuffing boxes leading into the first named connection operating to withdraw liquid leaking into the stuffing 30 boxes from the interior of the pump and return the same to the suction side of the pump.

3. In packing apparatus for a rotary pump, the combination of a shaft with stuffing boxes, a plurality of pump units on the shaft operating to develop high pressure in the liquid by stages, a connection from the pump for admitting quantities of the liquid under the pressure of the different stages 35 40 back into the suction side of the pump, and connections from the stuffing boxes leading into the first named connection operating to withdraw liquid leaking into the stuffing boxes from the interior of the pump and return the same to the suction side of the pump.

4. In packing apparatus for a high-speed rotary pump, the combination of a shaft with stuffing boxes, a plurality of pump units for developing high pressure in the liquid by stages, a pipe main, connections from the pump to the main for admitting quantities of the liquid at the different pressure stages to the main, a 50 connection including an ejector with a projecting discharge nozzle within the same connecting the main to the low pressure side of the pump, and connections from the stuffing boxes to the ejector operating to withdraw liquid leaking into the stuffing 55 boxes from the interior of the pump and 60

return the same to the suction side of the pump.

5. In packing apparatus for a high-speed rotary pump, the combination of a shaft 65 with stuffing boxes, a plurality of pump units for developing high pressure in a liquid by stages, a pipe main, connections from the pump to the main for admitting quantities of the liquid at the different pressure stages to the main, a connection including an ejector with a discharge opening for the high pressure liquid connecting the main to the low pressure side of the pump, and connections from the stuffing boxes to the 70 ejector for admitting the liquid leaking into the stuffing boxes from the interior of the pump into the ejector around the discharge opening, operating to return the same to the suction side of the pump, and means for regulating the pressure of the high-pressure liquid flowing through the ejector. 75

6. In packing apparatus for a high-speed rotary pump, the combination of a shaft 80 with stuffing boxes, a plurality of pump units for developing high pressure in the liquid by stages, a pipe main with valves, valved connections from the pump to the main for leading quantities of the liquid at the different pressure stages to the main, a connection including an ejector and a valve for connecting the main to the low pressure side of the pump, and connections from the stuffing boxes to the ejector operating 85 to withdraw liquid leaking into the stuffing boxes from the interior of the pump and return the same to the suction side of the pump, said valves operating to enable the pressure of the high-pressure liquid 90 passing through the ejector to be regulated. 95

7. In packing apparatus for a high-speed rotary pump, comprising different volutes for raising the pressure of a liquid by stages, the combination of a shaft with stuffing boxes, a pipe main, connections from the different volutes to the main for pumping quantities of the liquid at the different pressure stages to the main, a connection including an ejector connecting the main to the low pressure side of the pump, and connections from the stuffing boxes to the 100 ejector operating to admit liquid to the ejector at a higher pressure than the rise of pressure between the stages, and thereby withdraw liquid leaking into the stuffing 105 boxes from the interior of the pump and return the same to the suction side of the pump. 110 115

Signed at Los Angeles, California this 17th day of April 1925.
